AERIAL MINE

Erich Bickel, Baden, near Zurich, Switzerland

Application October 31, 1938, Serial No. 237,951
In Switzerland March 18, 1937

8 Claims. (Cl. 102—29)

The present invention relates to aerial mines suitable for air defense and of the type in which an explosive body, which I call the mine proper, is suspended in the air on a long, thin wire which is suspended from a carrier such as a parachute. Parachute, wire and mine proper are packed into a projectile and shot into the air either by rocket action or by a conventional anti-aircraft gun and unfold in the air at a predetermined point and in a predetermined manner. When the wire is hit by the aircraft to be destroyed the wire slides along the aircraft and the mine is rapidly pulled toward the aircraft where it explodes when it touches the aircraft.

The present invention is a modification of the invention set forth in my copending application Ser. No. 166,921, filed Oct. 2, 1937.

However, whereas in the device disclosed in the said copending application the parachute is unfolded first, then the wire is laid out and the mine proper moves ahead of the parachute up to the ceiling point of the projectile and then drops down leaving the parachute up above the mine and the wire in the final desired position, with the mine according to the present invention, the wire is laid out right away in final desired position having the mine proper already hanging at its lower end as long as the projectile ascends and the parachute is the last thing which is unfolded. In the projectile according to the present invention the mine proper is located at the rear end, the wire spool is in the center and the parachute is at the front or forward end and when the device is unfolded, the mine proper is first dropped, then the wire runs off its spool and finally the parachute is pulled out of the head of the projectile and is unfolded. The individual parts of the projectile are telescoped into one another so that they hold the projectile together until the moment or position in the air when or where the laying out of the mine is desired to start. The projectile comprises also a time fuse for detonating a small charge which causes throwing away of the shell containing the individual parts of the mine at the desired moment. The wire is preferably spooled on a stem which is situated in the longitudinal axis of the projectile. After removal of the shell the wire is unwound due to the revolving motion caused by the rifling of the gun. In order to assure constant unwinding action at the gradually reducing speed of the revolving motion of the projectile or rather the part left of it after unfolding, the configuration of the spool is slightly conical and the spool is wound

in layers which are unwound from the outside towards the inside.

The individual parts of which the projectile consists, when assembled, are secured against a revolving motion relatively to one another so that their relative position is not changed when the shot is fired and the rifling of the gun starts to act.

In the drawing an example of an embodiment of the present invention is shown:

Figure 1 is a longitudinal section of an air mine projectile according to the present invention.

Figure 2 diagrammatically shows various phases of the laying out operation of a mine according to the present invention.

Figure 3 diagrammatically shows a mine according to the present invention laid out in the air and ready for action.

Like letters and numerals indicate like parts in all figures of the drawing.

a is the head of the projectile which is provided with a time fuse b or a fuse responding to elevation above ground of conventional design. The shell c which contains the major parts of the aerial mine is pushed onto a. The interior of shell c is slightly conical so that it can easily be thrown off to the rear. Head a has a central stem f the diameter of which is reduced toward the rear of the projectile. Stem f is provided with a bore d containing a fuse composition which extends into the charge e at the bottom of the projectile. Charge e serves for removing the shell c to the rear at the desired moment. The mine proper g is located in the bottom end of shell c. The mine is provided with an impact fuse h of the type described in my copending application Ser. No. 237,950, filed Oct. 31, 1938, or of conventional construction.

46 The wire spool i is located in the center part of the projectile and rests on the mine proper g and abuts against the rims 1 and 2 of the head part a. The spool is wound in layers and slightly conical whereby the conical configuration is 45 preferably like that of the interior of shell c. The spool is pushed on the stem f which is preferably also slightly conical and acts as the spindle of the spool during unwinding. The parachute k is located in folded condition in the annular chamber in the head piece a around the stem f. Parachute k is connected by means of thin threads or cords 3 with the end of wire i at the lower inner end of the spool formed by said wire. The other end of the wire is at the upper outer portion of the spool and is connected

with the mine *g*. At the center of the parachute *k* is an opening *4* so that it can be symmetrically folded around the stem *f*; the opening *4* has a desirable aerodynamic effect during unfolding and sinking of the parachute.

Figure 2 in particular shows the mine being laid out; Fig. 2 is not to scale and the wire *i* is really much longer in proportion to the size of the other parts. The time fuse *b* ignites the throwing off charge *e* through the fuse in channel *d*; the resulting gas pressure pulls the shell *c* from the head *a* so that it can fall down. At first the mine *g* is pressed against the spool *i* and the latter against the rims *1* and *2* of the head piece *a* under the influence of the gas pressure. After disappearance of the pressure the mine is under the influence of air friction caused by the high speed at which the mine moves through the air. This air friction causes a separation of the mine from the spool whereby unwinding of the wire *i* is started. A small space *5* is provided between the spool *i* and the mine *g* into which space the gases caused by the ignition of the charge *e* enter and, due to their pressure, assist in separating the mine from the wire spool.

The wire is unwound from the spool in the same manner as is the thread from a shuttle in looms for weaving, i. e. it really is not unwound but pulled off. The pulling off action may cause too great stresses on the wire at the relatively high velocities at which the individual parts of aerial mine move when the mine is laid out and the wire is therefore wound in such manner that the rotation of the spool caused by the rifling of the gun assists the unwinding process and reduces the stresses on the wire. The wire is wound so that the direction of rotation of the spool necessary for unwinding coincides with the direction of rotation of the spool caused by the rifling of the gun and indicated by means of arrow *6* in Fig. 2.

Removal of the parachute *k* from head piece *a* is not possible until the wire *i* is completely unwound. Then the parachute is free and is pulled out of the head piece *a* whereby it is stretched out. The head piece, being of greater weight, moves a little farther forward due to forces of inertia and then falls to the ground. Unfolding of the parachute does not take place until the mine *g* has acquired a certain speed and wire *i* is stretched out. Then the air friction is great enough to unfold the parachute. At this moment the whole wire is already stretched out and the device is fully ready for action.

The laid out mine, wire and parachute is diagrammatically shown in Fig. 3. The wire, in fact, is much longer in proportion to the other parts shown in Fig. 3 as could be indicated in said figure; that is why the wire is shown broken in Fig. 3.

The mine is already effective for air defense as long as the wire is unwound and only the shell *c* is thrown away because at this time the mine proper *g* hangs freely on the wire. If an aircraft crosses the wire the pulling up effect is increased by the forward motion of the spool and head piece. Also the mine *g* itself, due to forces of inertia, moves upward toward the aircraft to be destroyed so that the action of the new aerial mine is very quick also while it is laid out. The operation of the anti-aircraft guns projecting mines, according to the present invention, into the air is therefore the same as when shooting conventional shrapnels; there is one difference:

the gun must be aimed somewhat more ahead of the aircraft to be brought down and the timing of the time fuse can be less accurate.

If the projectile must be confined to very small calibers, the shell *c* can be much reduced in size or completely omitted. Such embodiments of the present invention are shown in Figs. 4 and 5.

In the embodiment according to Fig. 4, the shell *7* covers only part of the mine proper *8*. The stem *9* extends into the mine *8* and shell *7* is pushed onto the mine.

In Fig. 5, an embodiment of the present invention is shown where the charge *10* for disassembling the device in the air is arranged between the mine proper *11* and the wire spool *i*. No shell is provided. The stem *12* extends into the mine proper and has lateral openings *13* to provide an outlet for the fuse *d*.

The parts which are pushed into one another may be provided with projections and recesses *14* in Fig. 1, *15* in Fig. 4, and *16* in Fig. 5 to prevent relative rotational displacement.

Characteristic for all embodiments of the present invention is that when the device is unfolded in the air, first the mine proper is separated, then the wire is unwound and then the parachute is released and unfolded.

While I believe the above described embodiments of my invention to be preferred embodiments, I wish it to be understood that I do not desire to be limited to the exact details of method, design and construction shown and described, for obvious modifications will occur to a person skilled in the art.

I claim:

1. An air defense device comprising a projectile having a head piece provided with a substantially annular cavity, a parachute folded therewithin, a wire connected at one end with said parachute and being coiled into a compact spool body closing said cavity, and an explosive bomb connected with the other end of said wire, said folded up parachute, said spool and said bomb all having substantially the same outside diameter and being positioned coaxially and in line with and directly adjacent to one another, and a separating charge disposed for acting between said bomb and said spool body for separating said bomb from said spool body.

2. An air defense device comprising a projectile having a substantially hollow head piece, a parachute folded therewithin, a shell having a closed bottom portion, a wire connected at one end with said parachute and being coiled into a compact spool body, an explosive bomb connected with the other end of said wire and disposed in said bottom portion, said folded up parachute, said spool and said bomb all having substantially the same outside diameter and being positioned coaxially and in line with and directly adjacent to one another, a stem member rigidly connected with the interior of said headpiece and extending centrally through said headpiece, through said folded up parachute, and through said spool body, and a bursting charge disposed in said bottom portion adjacent to said bomb for removing said shell and setting free said bomb.

3. An air defense device comprising a projectile having a substantially hollow headpiece, a parachute folded therewithin, a shell member having a bottom portion, a wire connected at one end with said parachute and being coiled into a compact spool body, an explosive bomb connected with the other end of said wire and disposed in

said shell, said folded up parachute, said spool and said bomb all having substantially the same outside diameter and being positioned coaxially and in line with and directly adjacent to one another, a stem member rigidly connected with the interior of said headpiece and extending centrally through said headpiece, through said folded up parachute, into said spool body and through said bomb, and a bursting charge disposed in said bottom portion adjacent to said bomb for removing 10 said shell member and setting free said bomb.

4. An air defense device comprising a projectile having a substantially pointed hollow forward portion having an open rear end, a stem member rigidly connected with the interior of said portion and extending centrally therethrough, a parachute folded within said forward portion and around said stem member, a wire connected at one end with said parachute and being coiled around said stem member and forming a compact spool body disposed in line and coaxially with and directly adjacent to said folded up parachute and closing the open rear end of said hollow forward portion, an explosive bomb connected with the other end of said wire and being positioned coaxially and in line with and directly abutting against said spool body, and a separating charge disposed between said spool body and said bomb for separating said bomb from said spool body.

5. An air defense device comprising a projectile having a substantially pointed hollow forward portion having an open rear end, a stem member rigidly connected with the interior of said portion and extending centrally therethrough, a parachute folded within said forward portion and around said stem member, a wire connected at one end with said parachute and being coiled around said stem member and forming a compact spool body disposed in line and coaxially with and directly adjacent to said folded up parachute and closing the open rear end of said hollow forward portion and forming the middle portion of said projectile, an explosive bomb connected with the other end of said wire and removably connected with said stem member and coaxially and in line with and directly abutting against said spool body and forming the rear end of said projectile, and a separating charge disposed adjacent to said bomb and to said stem member for liberating said bomb.

6. An air defense device comprising a projectile having a headpiece provided with a substantially annular cavity, a parachute folded therewithin, a wire connected at one end with said parachute and being coiled into a compact spool body, and an explosive bomb connected with the other end of said wire, said folded up parachute, said spool and said bomb all having substantially the same outside diameter and being positioned coaxially and in line with and directly adjacent to one another, said spool body having a cavity closed by said bomb, and a separating charge disposed in said cavity of said spool body for separating said

bomb from said spool body at a predetermined moment.

7. An air defense device comprising a projectile having a substantially pointed hollow forward portion having an open rear end and containing an automatically actuated fuse, a hollow stem member rigidly connected with the interior of said portion and extending centrally therethrough, a parachute folded within said forward portion and around said stem member, a wire connected at one end with said parachute and being coiled around said stem member and forming a compact spool body disposed in line and coaxially with and directly adjacent to said folded up parachute and closing the open rear end of said hollow forward portion, an explosive bomb connected with the other end of said wire and being positioned coaxially and in line with and directly abutting against said spool body, said spool body having a cavity closed by said bomb, a separating charge disposed substantially at the rear end of said bomb, said fuse extending through said stem member, said cavity and said bomb into said separating charge, the pressure produced when said fuse and charge is burnt acting in said cavity and separating said bomb and spool body.

8. An air defense device comprising a projectile having a substantially pointed hollow forward portion having an open rear end, a stem member rigidly connected with the interior of said portion and extending centrally therethrough, a parachute folded within said forward portion and around said stem member, a wire connected at one end with said parachute and being coiled around said stem member and forming a compact spool body having a substantially cylindrical outside surface and being disposed in line and coaxially with and directly adjacent to said folded up parachute and closing the open rear end of said hollow forward portion, an explosive bomb connected with the other end of said wire and being positioned coaxially and in line with and directly abutting against said spool body, the portion of said spool body adjacent to said bomb having a substantially flat annular surface abutting against said bomb and having a smaller diameter than the outside diameter of said body, said spool body flaring from said surface outward to the cylindrical outside surface of said body and forming an annular recess, said spool body flaring inward from said surface towards the center of said body and forming a centrally located cavity, said bomb having a substantially cylindrical configuration of substantially the same diameter as said spool body, an impact fuse member extending from said bomb into said annular recess, and a separating fuse disposed in said forward portion and extending through said stem member and said cavity, said cavity being filled with high pressure gases when said fuse is actuated for separation of said bomb from said spool body.
